(57) **CLAIM**

The ornamental design for a vehicle muffler, as shown and described.

DESCRIPTION

FIG. 1 is a front view of first embodiment of a vehicle muffler showing my new design.

FIG. 2 is a back view thereof.

FIG. 3 is a top view thereof.

FIG. 4 is a bottom view thereof.

FIG. 5 is a right side view thereof.

FIG. 6 is a left side view thereof.

FIG. 7 is a front view of second embodiment of a vehicle muffler showing my new design.

FIG. 8 is a back view thereof.

FIG. 9 is a top view thereof.

FIG. 10 is a bottom view thereof.

FIG. 11 is a right side view thereof.

FIG. 12 is a left side view thereof; and,

FIG. 13 is a cross sectional view along a line 13-13 in FIG. 7.

The broken lines in the drawings illustrate portions of the vehicle muffler that form no part of the claimed design.
